INVENTOR.
Emanuel M. Mellinger

BY

Richard B. Oliver

ATTORNEY.

UNITED STATES PATENT OFFICE.

EMANUEL M. MELLINGER, OF GRIDLEY, CALIFORNIA.

RAIL CHAIR.

Application filed July 18, 1927. Serial No. 206,618.

This invention relates to improvements in rail chairs and has as its general object to provide a rail chair which will be more substantial than the ordinary chair and which 5 will effectually brace the rail supported thereby and, where employed in supporting the meeting ends of two rails, will effectually prevent relative displacement of the rail ends as well as minimizing the clicking noise 10 incident to travel of the train wheels over the said ends of the rails.

Another object of the invention is to so construct the base of the rail chair and the fish plates associated therewith as to pre- 15 clude any displacement of the fish plates either with respect to the base plate or with respect to the rail supported by the chair, so that, while bolts are employed in securing the fish plates to the rail, at the same 20 time the construction is such that in the event of the bolts becoming loosened, the fish plates will still retain their clamping engagement with the opposite sides of the supported rail so that the efficiency of the 25 device is not appreciably impaired.

Another object of the invention is to provide a rail chair, which, in one embodiment, may be employed upon curved stretches of track to support the outer rail at the proper 30 elevation thus obviating the necessity of ballasting the outer ends of the ties on such a track to cause the ties to assume an inclined position.

In the accompanying drawings: 35 Fig. 1 is a plan view of a rail chair constructed in accordance with the present invention and designed for use on a straight track, the view illustrating the chair employed in supporting the meeting ends of 40 two rails;

Fig. 2 is a side elevation of the chair; 45 Fig. 3 is a vertical transverse sectional view through the chair, the view likewise illustrating the rail and the tie in section; Fig. 4 is a fragmentary perspective view of one end of the face plate of the chair;

Fig. 5 is a similar view of one end of one of the fish plates of the chair;

Fig. 6 is a fragmentary plan view of a 50 rail chair embodying the invention and constructed for employment on a curved stretch of track;

Fig. 7 is a side elevation of the rail chair shown in Figure 6;

Fig. 8 is a vertical transverse sectional

view through the rail chair shown in Figures 6 and 7;

Fig. 9 is a fragmentary perspective view of one end of the face plate of the chair.

The base plate of the rail chair embodying the invention, in that form shown in Figures 1 to 4 inclusive, is indicated in general by the numeral 1 and comprises a rail seating portion 2 upon which the base flanges 3 of the rail 4 are designed to rest, the upper surface of the seating portion being flat and the sides of the said portion being defined by shoulders 5 which are of a depth equal substantially to the thickness of the rail base flanges 3 at their outer edges, the 70 said edges of the base flanges abutting the shoulders as clearly shown in Figure 3 of the drawings. The base plate 1 is formed upon its upper side, at the opposite sides of the seating portion 2 with longitudinally extending, upstanding heads 6 which are approximately semi-circular in cross section, these heads extending the entire length of the base plate of the chair and each head being formed with a longitudinally extending 75 channel 7 which is of cylindrical contour and which opens through the inner face of the respective head 6 by way of a substantially horizontally disposed slot 8, the channel and slot extending throughout the entire length 80 of the respective head 6. It will be observed by reference to Figures 3 and 4 of the drawings that the bottom wall of each slot 8, at its outer side, meets the upper edge of the respective shoulder 5 so that the lower side 90 of each slot 8 is in a plane with the upper side of the respective base flange 3 of a rail disposed upon the seating portion 2 of the base plate. In order to obviate any likelihood of contact of the wheel flanges with the 95 base plate 1, the heads 6 thereof are preferably both vertically and transversely rounded at their ends as indicated by the numeral 6^x and likewise the corners of the said base plate are both transversely and vertically rounded as indicated by the numeral 100 6^y, as clearly shown in Figures 1 and 2 of the drawings.

Fish plates, indicated in general by the numeral 9, are employed in connection with the base plate and each of these fish plates comprises an upstanding body portion 10 provided at its upper edge with a seating shoulder 11 of a contour to be squarely engaged by the under side of the head of the 110

rail at the respective side of the said rail, the seating shoulder being of a width slightly greater than the width of the head of the rail at the under side thereof between the web of the rail and the outer face of the said head, and the upper side of the seating shoulder, beyond the plane of the side of the rail head being curved downwardly and outwardly. Each fish plate further includes a base portion 12 which rests upon the upper side of the respective base flange of the rail, the upstanding bodies 10 of the fish plates being disposed against the opposite sides of the web of the rail, and the said base portion is inclined downwardly to correspond with the downward inclination of the upper surface of the base flange of the rail and of a width to extend over the said upper face, the portion 12, beyond the inclined portion being extended horizontally to provide a portion 13 which is of dimensions to be snugly received within the slot 8 in the corresponding head 6 of the base plate 1. The portion 13 of each fish plate terminates in a bead 14 which is of approximately cylindrical contour and of a diameter to fit snugly within the channel 7 in the manner clearly shown in Figure 3 of the drawings, the bead being of course of a diameter greater than the thickness of the extended portion 13 of the base 12 of the respective fish plate. In assembling the fish plates with the base plate 1 of the chair, after the chair has been disposed upon the ties, indicated in the drawings by the reference letter T, and the rail, or the rails, if there are two to be supported by the chair, disposed upon the seating portion 2 of the chair base plate 1, the fish plates are slid into engagement with the base plate and rail or rails, the beads 14 and extended portions 13 of the fish plates fitting snugly in the channels 7 and slots 8 respectively, of the respective heads 6. With the parts thus assembled, the upstanding bodies 10 of the fish plates will snugly embrace the opposite sides of the web of the rail and the seating shoulders 11 will snugly engage the under side of the head of the rail. Securing bolts 15 are then secured through aligned openings in the fish plates and rail web and spikes 16 are driven through openings 17 formed in the outer marginal portions of the base plate 1 and into the ties T.

It will be evident that inasmuch as the upper and under sides of the extensions 13 of the base portions 12 of the fish plates are in abutting relation to the walls of the slots 8 in the respective heads 6, there will be no likelihood of upward displacement of the fish plates and the base flanges will be held firmly upon the rail seat 2. It will also be evident that there can be no relative displacement of the meeting ends of two rails supported by the chair, in a vertical direc-

tion, and consequently the usual clicking noise which is produced by the passage of the train wheels over the ends of railway rails is minimized.

The embodiment of the invention illustrated in Figures 6 to 9 inclusive is identical with the embodiment just described except that, whereas in the first described embodiment the upper surface of the rail seating portion 2 of the base plate 1 is parallel to the under surface of the plate and therefore horizontal when the chair is established in position upon the tie on a straight stretch of track, in the modified structure the upper side of the rail seating portion of the base plate is inclined downwardly from one side to the other at a greater or less angle as most clearly shown in Figures 8 and 9 of the drawings and in accordance with the degree of curvature of the track rails to be supported by the chair.

Inasmuch as, as previously stated, the embodiment shown in Figures 6 to 9 inclusive is identical with the embodiment shown in Figures 1 to 5 inclusive, except in the respect above outlined, parts in Figures 6 to 9 inclusive corresponding to parts in Figures 1 to 5 inclusive are indicated by the corresponding reference numerals with the addition of the exponent "a."

It will be evident that due to the inclination of the upper side of the rail meeting portion 2 of the base plate of the chair shown in the said Figures 6 to 9 inclusive, the outer rail, of a curved section of track, supported by the chair, will be suitably elevated with respect to the inner rail, thus obviating the necessity of so ballasting the ties at the curve as to effect elevation of the outer rail as is now customary.

It is to be understood, of course, that various changes may be made, within the scope of what is claimed, without departing from the spirit of the invention.

Having thus described my invention, what I claim is:

1. A rail chair comprising a base plate having a rail seating portion, heads extending longitudinally of the plate at opposite sides of the said seating portion thereof and provided with longitudinal channels and with slots leading from the sides of the channels and opening through the opposing sides of the head, and fish plates having upstanding rail clamping members and base members, the said base members of the fish plates being provided with marginal portions fitting in the said slots in the head and with enlarged longitudinal beads fitting in the channels of the respective heads.

2. A rail chair comprising a base plate having a rail seating portion, heads extending longitudinally of the plate at opposite sides of the said seating portion thereof,

each of the heads having an approximately cylindrical channel formed longitudinally therein and having a slot formed therein extending between one side of the channel and the inner side of the head and opening therethrough, and fish plates having upstanding rail clamping members and base members, the said base members of the fish plates being provided with portions fitting in the slots in the respective heads of the base plate and with approximately cylindrical beads fitting in the said channels.

3. A rail chair comprising a base plate having a rail seating portion, heads extending longitudinally of the plate at opposite sides of the said seating portion thereof, each of the heads having an approximately cylindrical channel formed longitudinally therein and having a slot formed therein extending between one side of the channel and the inner side of the head and opening therethrough, and fish plates having upstanding rail clamping members and

base members, the said base members of the fish plates being provided with portions fitting in the slots in the respective heads of the base plate and with approximately cylindrical beads fitting in the said channels, the base members of the fish plates being downwardly inclined to seat upon the inclined upper sides of the respective base flanges of a rail disposed upon the seating portion of the base plate, the said slots in the heads and the portions of the base members of the fish plates which are engaged in said slots being substantially horizontally disposed, the bead of each fish plate base member being of a diameter greater than the thickness of the slot-engaging portion of the base member whereby the base members of the fish plates have interlocking engagement with the head of the base plate.

In testimony whereof I affix my signature.

EMANUEL M. MELLINGER.
